DEVICE FOR INSERTING NECKS IN BOX BODIES

Johannes Schmiedel, Dresden, Germany, assignor to Johann Carl Müller, Dresden, Germany, doing business under the firm name and style of "Universelle" Cigarettenmaschinenfabrik J. C. Mueller & Co.

Application February 25, 1939, Serial No. 258,431
In Germany February 28, 1938

8 Claims. (Cl. 93—55)

This invention relates to a device for inserting necks in box bodies.

It is known to insert a neck in a box body by introducing a box body in a neck inserting device and then inserting a neck from above by means of a piston which presses the neck on all four sides against the inner wall of the body. To prevent troubles during insertion of a neck and to insure the smooth introduction thereof into the body of a box the known devices employ fingers or feelers which during the inserting step move between the inner wall of the body and the neck or piston.

In one of the known devices the necks are inserted during the forward motion of the box bodies while the two conveying paths simultaneously approach one another. The invention refers to this latter group of devices, and has for its object to provide for a relatively large output. According to the invention, operating speed is increased by omitting any reciprocating motion of pistons while permitting intermittent and continuous operation. For this purpose, the neck strip lying at first flat after having been glued and opened out into a rectangular form is caught at its front boundary line by tongs, bent inwardly on that side and conveyed to the inserting station. Then the other three sides of the neck strip are engaged by control means and also bent inwardly, whereupon the control means place the strip in proper position relative to the box body and then tilt it into the plane of the box so that the neck enters the body of the box.

The tongs engaging the necks may move in a closed path in such manner that the necks are gripped from above, then conveyed and thereupon released again, whereupon the tongs return to initial position. The path of motion of the tongs may have the form of a rectangle or any other form, particularly with respect to the return stroke. The tongs may be so formed that their inner leg engages the neck at full height and the outer leg grips the neck above the glue line. At the point where the neck is introduced into the body of the box means may be provided for retaining the neck when released by the tongs.

The said control means for gripping and bending the neck strip and introducing it into a body consist of pressure members which place themselves around two adjacent corners and besides a swinging-in motion carry out a tilting motion into a plane of the box. Before being caught by the pressure members, i. e., while they are still being brought into the introducing station by the tongs, the necks with their top edges enter under

guide surfaces which are laterally disposed and cooperate in the tilting motion carried out by the pressure members during the inserting step. The swinging motion of the pressure members and the tilting motion of the members and guide surfaces are brought about by separate drives, the tilting motion being performed about an axis lying in the height of the upper front edge of the box.

The invention is illustrated by way of example in the accompanying drawing, in which

Figure 1 is a side view of the device and shows a position at which the tongs have just conveyed a neck up to the inserting place;

Fig. 2 is a side view showing the position at which the tongs have released the neck; and

Fig. 3 is a top view of the device in general.

The neck strips 1 are in known manner in folded condition moved between and past the gluing means 2 and provided with glue somewhat below the center of their width. They are then conveyed within range of a suction plate 18 and of two levers 3, 4 which by turning it 90° fold out the neck strip to form a closed rectangle as shown in Fig. 3.

The bodies are moved in known manner by a chain type or other conveyor 5 provided with drivers 6 in the direction of the arrow a, Fig. 2. The conveying path for the bodies 7 ascends near the inserting station so that the paths for the necks 1 and bodies 7 are approaching one another. When the boxes are within the inserting station, one or more stops 8 enter their path to straighten the boxes which thus are in a position ready to receive the necks 1 on reaching the station.

The necks 1 are also conveyed in the direction of the arrow a by the tongs 9 which for instance carry out the closed advance motion b shown in Figs. 1 and 2. The tongs engage the front side of a neck 1. The jaws of the tongs 9 are bent toward the inside of the neck or curved, as indicated in Fig. 3. The inwardly disposed jaw 10 extends over the entire height of the neck while the outer jaw 11 grips the neck only above the glue lines.

Having the rectangular form, the necks 1 are caught by the tongs 9 at the front side when the tongs are in extreme left-hand position and have moved down. The tongs then move to the right and engage the neck 1. Within the inserting place guide surfaces 12 are provided under which moves the upper edge of the neck 1. Furthermore, near the end of the conveying way of the neck securing means having the form of strip-

pers 22 are disposed for retaining the neck released by the tongs 9, 11 and serve later on as guide rails for the bodies having received their necks.

5 Within the inserting place pressure members of angular shape are, moreover, provided which are designated 14 and rotate about the shafts 13. Their actual pressure applying portions of acute-angled form embrace the outer circumference of 10 the neck 1 and bend it inwardly also on the other three sides, as shown in Fig. 3.

The pressure members 14 are swung in and out by being moved about the pivots 13. The toggle levers 15 carrying the members 14 are actuated at their free ends by control rods 16. 17 is the joint control shaft for the rods 16. Between the drive 17 and the control rods 16 universal joints 19 are interposed.

Besides carrying out a rotary motion about the 20 pivots 13 the pressure members 14, together with the guide faces 12, perform also a tilting motion from the plane of the conveying path of the necks 1 into the plane of the box bodies 7 for the purpose of inserting the necks in the bodies. 25 Tilting is effected about a shaft 20 by means of a drive 21, the tilting axis 20 lying in the height of the upper front edge of the body 7.

The mode of operation is as follows:

Having been moved past the gluing device 2 30 the necks 1 in closed condition pass within range of the opening means 3, 4 which open the necks to form a rectangular form. Then the jaws 10, 11 of the tongs 9 grip the front side of the neck, bend it to the middle of the neck. During their 35 forward motion the jaws 10 and 11 take along the neck which in this way enter under the guide surfaces 12. Simultaneously with the neck 1 the box body 7 is advanced also so that both on arriving at the inserting station are already partly 40 engaged, the stop 8 imparting to the body 7 the proper position and supporting it. The rear end of the neck 1 is then engaged by the pressure members 14 above the glue line, and the other three sides are thus bent inwardly. Then the 45 pressure members 14 and the guide faces 12 tilt about the axis 20 into a plane of the body 7, whereby the neck 1 is inserted. In the meantime, the tongs 9 have opened their jaws and return to initial position to get a fresh neck 1. 50 After insertion of the neck 1 in the body 7 the members 13, 14 move upwards and the pressure members 14 open to grip another neck.

I claim:

1. A device for inserting necks of cardboard or 55 like material in box bodies in which the necks

are inserted after the forward motion of the boxes, having conveyor means in two inclined planes approaching each other, comprising means for gluing a neck while lying at first flat and opened out into a rectangular form, tongs 5 for catching the neck at its front side for bending the front side of the neck towards the middle of the opened neck, means for conveying the neck in this form to a finished body of the box to be inserted therein, control means for gripping the other three sides of the neck and bending them 10 towards the middle of the neck, means for tilting the control means for entering the neck with its full circumference into the plane of the box, and means releasing the control means from the 15 neck.

2. A device according to claim 1, in which the tongs gripping the front side of the neck with their legs bent toward the inside of the neck carry out a closed path for gripping and conveying 20 the neck, releasing the neck and then returning to initial position above the conveying paths of the necks lying above the conveying part for the box bodies.

3. A device according to claim 1, in which the tongs with their inner leg embrace the neck over 25 its full width and with their outer leg above the glue line.

4. A device according to claim 1, in which at the place where the neck is inserted in the box 30 body securing means are provided for retaining the neck when released by the tongs.

5. A device according to claim 1, in which the control means for gripping and bending the second, third and fourth side of the neck and introducing 35 the neck consist of pressure members which embrace the two rear corners of the neck and which besides a swinging motion in the plane of the neck perform also a tilting motion into the plane of the box.

6. A device according to claim 1, in which on 40 passing to the inserting station the necks enter with their upper edge under guide surfaces which cooperate in the tilting motion performed by the pressure members.

7. A device according to claim 1, in which the 45 swinging motion of the pressure members and the tilting motion of the pressure members and guide faces are effected by separate drives.

8. A device according to claim 1, in which the 50 turning axis for the tilting motion of the pressure members and guide faces is located in the height of the upper front edge of the box.

JOHANNES SCHMIEDEL. 55
